UNITED STATES PATENT OFFICE.

TIMOTHY MURRAY AND FREDERICK W. BRITTIN, OF BIRMINGHAM, CONN.

DESIGN FOR A FORK.

SPECIFICATION forming part of Design No. 16,169, dated July 14, 1885.

Application filed June 1, 1885. Term of patent 3½ years.

To all whom it may concern:

Be it known that we, TIMOTHY MURRAY and FREDERICK W. BRITTIN, citizens of the United States, residing at Birmingham, in the county of New Haven and State of Connecticut, have invented and produced a new and original Design for Forks, of which the following is a specification, reference being had thereto to the accompanying drawings.

10 Figure 1 is a side elevation of our newly-designed fork; Fig. 2, a plan view slightly modified, a groove or crease being made around the bulb; Fig. 3, a cross-section on the line x—x in Fig. 1; and Figs. 4 and 5 are similar cross-sections, the shape of the shank being slightly changed, but without changing the general appearance of the design.

15 The leading features of our design consist in a tapering diamond-shaped shank and a bulb or ellipsoid which connects the handle with the base.

20 A is the handle, B the base, and C the tines. These may be of any ordinary form, although we preferably make them of the form illustrated in the drawings. D is the shank, and 25 E the bulb or ellipsoid.

25 Viewed in plan, the narrowest place in the fork is at the junction of the shank with the base, as at F, and the widest place is near the outer end of the handle, as at G. Between 30 these points the outline of the parts falls within a straight line drawn from one point to the other, the sides of both handle and shank be-

ing straight lines. In side elevation the widest place is at the section-line x—x. From this 35 point the outline is a straight line to the point indicated by F, and in the other direction the outline falls within a straight line drawn to the end of the handle. Between the inner end of the handle and the outer end of the shank 40 the outline, both in plan and in elevation, trends first downward, then curves outward to form the bulb or ellipsoid E. As stated above, the general shape of the shank in cross-section is that of a diamond. 45

We claim—

The design for forks herein shown and described, the same consisting of the diamond-shaped shank tapering evenly from the base outward, the handle whose sides form a straight 50 line with the shank from its inner end to near its outer end, and a bulb or ellipsoid between said shank and handle, whose outline in plan falls within a line drawn from the narrowest part of the shank to the widest part of the 55 handle, the outline of the bulb and handle in elevation falling within a line drawn from the outer end of the shank to the end of the handle.

In testimony whereof we affix our signatures 50 in presence of two witnesses.

TIMOTHY MURRAY.
FREDERICK W. BRITTIN.
